Primary Examiner — Mary Shannon Malley*Assistant Examiner* — Dustin Andrew Griffith(74) *Attorney, Agent, or Firm* — QuickPatents, LLC; Kevin Prince(57) **CLAIM**

The ornamental design for a belt-attached item holder, as shown and described.

DESCRIPTION

FIG. 1 is a perspective view of a belt-attached item holder showing the design in its environment;

FIG. 2 is an enlarged front perspective view thereof;

FIG. 3 is an enlarged rear perspective view thereof;

FIG. 4 is a front elevational view thereof;

FIG. 5 is a rear elevational view thereof;

FIG. 6 is a right-side elevational view thereof, the left-side elevational view being a mirror image thereof;

FIG. 7 is a top plan view thereof; and,

FIG. 8 is a bottom plan view thereof.

The broken lines depicting a person and a drill depict environmental subject matter and forms no part of the claimed design.

1 Claim, 4 Drawing Sheets(56)
